[57] CLAIM

The ornamental design for a faucet, substantially as shown and described.

DESCRIPTION

FIG. 1 is a perspective view taken from the top, front and right side of a faucet showing my new design; FIG. 2 is a left side elevational view thereof, the right side being a mirror image of the left side shown; FIG. 3 is a rear elevational view thereof; FIG. 4 is a top plan view thereof; and FIG. 5 is a bottom plan view thereof. The broken line representation of supply pipes in FIG. 1 is for purposes of illustration only and forms no part of the claimed design.
